UNITED STATES PATENT OFFICE.

MAURICE LEBLANC, OF CROISSY, FRANCE, ASSIGNEE TO WESTINGHOUSE ELECTRIC & MANUFACTURING COMPANY, A CORPORATION OF PENNSYLVANIA.

APPARATUS FOR THE REMOVAL OF COAL-ASH.

1,254,244.

Specification of Letters Patent. Patented Jan. 22, 1918.

Application filed May 9, 1914. Serial No. 837,557.

To all whom it may concern:

Be it known that I, MAURICE LEBLANC, a citizen of the Republic of France, and a resident of Croissy, Seine-et-Oise, France, whose post-office address is Val-sur-Seine, Croissy, Seine-et-Oise, France, have made a new and useful Invention in Apparatus for the Removal of Coal-Ash, of which the following is a specification.

10 This invention relates to improved apparatus for removing the ashes from stoke holes especially on board ship, which apparatus may also be employed as a bilge pump.

It has heretofore been suggested to employ for removing ashes, especially from marine furnaces, either some kind of centrifugal pump the rotor of which is traversed by the ashes thus giving rise to very rapid wear, or a high pressure water jet 20 which is caused to travel along the longitudinal axis of the evacuation pipe into which the ashes are introduced. In this case the output will be very low owing to the high pressure required.

25 The object of the present invention is to construct an improved apparatus in which the above disadvantages are avoided and according thereto the ashes are withdrawn by contact with water which is caused to flow 30 through a converging-diverging nozzle the converging portion of the nozzle being adapted to be moved longitudinally in order to open and close the entry port for the ashes so that the starting of the apparatus 35 can be safely and readily effected.

The apparatus is illustrated in the accompanying drawing in which Figure 1 is a longitudinal section of the improved apparatus, Fig. 2 a section on the line 11—11 of 40 Fig. 1, and Fig. 3 an elevation showing the apparatus with a feed pump and its propelling motor.

45 Referring now to Figs. 1 and 2, the water nozzle is provided with a diverging member 1 and a converging member 2 which is longitudinally movable by means of a rack 3 engaging with a toothed sector 4 operated by a lever 5. Said lever carries a catch 6 the function of which is 50 hereinafter explained. Other means may be provided for moving the converging member 2 if desired. 7 is a charging casing

which may be provided with a hopper 8, said casing being connected with the converging-diverging nozzle 1, 2, through a circular orifice 9 of the same diameter as the narrowest part of the diverging member 1 of the nozzle. A damper 10 operated by a suitable handle 11 is provided for closing the bottom of the hopper 8.

60 The operation of the apparatus is as follows: The converging member 2 of the nozzle having been moved toward the diverging member of the nozzle by rotating the lever 5 in the counter-clockwise direction the apparatus is primed by admitting water under pressure to the nozzle. The lever 5 is then rotated in the clockwise direction so as to withdraw the converging member 2 of the nozzle from the diverging member 1 and open 65 the orifice 9 from the casing 7. The damper 10 having been withdrawn so as to open the bottom of the hopper 8 the ashes will be precipitated through the casing and into the nozzle being discharged through the diverging member 1.

70 It will be noticed that in consequence of the partial vacuum created in the lower part of the casing 7 by the flow of water through the nozzle the ashes naturally tend 75 to fall into the nozzle by reason of the atmospheric pressure above them and it will furthermore be observed that since the admission orifice 9 is of substantially the same area as the narrowest part of the diverging member 1 it is impossible for any choking to occur.

75 In Fig. 3 the apparatus above described is shown provided with a centrifugal feed pump 12 driven by an electric motor 13, 80 placed in any convenient position and connected through a valve 16 with the apparatus. This figure also shows by way of example various safety devices, namely a non-return valve 14 at the end of the diverging member 1 of the nozzle which prevents any backward return of water in the case of a failure of the water under pressure supplied from the pump 12. 15 is a lock provided on the electric motor starter said 85 lock being connected to the catch 6 on the lever 5, and preventing the starter from being moved from its initial or zero position until the lever 5 has been turned to the left,

that is to say unless the converging member of the nozzle is in the position in which the port from the casing 7 is closed.

It will be observed that a similar arrangement

5 may be employed for preventing the operation of the water pump when this is not driven by an electric motor but by some other kind of motor, or when some other source of water under pressure is provided,

10 it being only necessary of course to prevent the opening of the water valve 16 before the converging member 2 of the nozzle has been moved to its lower position in which the ori-

fice 9 is closed.

15 It may be further pointed out that in case of a stoppage of the current of water through wrongful operation of the apparatus, the damper 10 can be used to prevent the flow of water back into the furnace.

20 The apparatus hereinbefore described can also be employed as a bilge pump, the bilge water being withdrawn by friction with the water jet between the converging member 2 and the diverging member 1 of the nozzle.

25 The feed pump for supplying the water jet can be placed in any situation and consequently sufficiently above the floor of the stoke-hold to render it impossible for it to be flooded.

30 Having now particularly described and

ascertained the nature of my said invention and in what manner the same is to be performed, I declare that what I claim is:

1. In a device of the character described, a hopper for delivering ash, a two part nozzle, one part of which is longitudinally adjustable with relation to the other part, means for delivering actuating water to said nozzle and means dependent on the relative positions of said parts for controlling the 40 starting operation of said water delivery means.

2. In a device of the character described, a two part nozzle having an intake port formed between the parts thereof, one of the 45 parts of the nozzle being longitudinally adjustable with relation to the other to close the port, means for delivering actuating liquid to said nozzle and means dependent on the relative positions of the parts of said 50 nozzle for controlling the starting operation of said liquid delivering means.

In testimony whereof, I have hereunto subscribed my name this 25th day of April, 1914.

MAURICE LEBLANC.
